UNITED STATES PATENT OFFICE.

SAMUEL DYER AND FRANK P. DYER, OF MUNCIE, INDIANA.

BORING-BAR.

No. 819,743.

Specification of Letters Patent.

Patented May 8, 1906.

Application filed November 11, 1904. Serial No. 232,315.

To all whom it may concern:

Be it known that we, SAMUEL FRANK P. DYER, citizens of the United States, residing at Muncie, in the county of Delaware and State of Indiana, have invented a new and useful Improvement in Boring-Bars, of which the following is a specification.

Our invention relates to an improved boring-bar and the sleeves carried by said bar and in turn carrying the cutters and an improved lever for adjusting the bar.

Heretofore boring-tools have been supported by being set in a tool-post and fastened or clamped at one end only, the tool projecting a foot or more, with the result that when the tool would strike a ridge or hard spot it would spring away, rendering it difficult to get an accurate bore.

The object of our invention is to support the bar at each end either concentrically or eccentrically, to provide means for sliding the cutter along said bar, to provide means whereby the cutter can be brought to and from the work at will, and also to provide a plurality of interchangeable parts, so that all classes of work can be done, the same guiding-bar being used for the various cutters and sleeves.

Our invention consists in the novel features of construction and combination of parts hereinafter described, particularly pointed out in the claims, and shown in the accompanying drawings, in which—

Figure 1 is a perspective view of our boring-bar in position for use applied thereto. Fig. 2 is a plan view of a sleeve and cutter-head. Fig. 3 is an end view of the cutter-head shown in Fig. 2. Fig. 4 is a view in side-elevation, showing the cutter-head end portion of the sleeve, the head being removed. Fig. 5 is a longitudinal section through a sleeve, the lever being also shown in section and the bar being shown partly in section and partly in elevation. Fig. 6 is an end view of the bar, showing the lever and sleeve tail or shank. Fig. 7 is a detail view of the sleeve and cutter-head shown in section in Fig. 5, the central portion of the sleeve being broken away, the head and front end being in plan, and the rear end, shank, and lever-collar being in section. Fig. 8 is a section on the line 8 8 of Fig. 7, illustrating the position

of the cutter-head with reference to the article operated on, the latter being shown in dotted lines. Fig. 9 is a perspective view of a cutter-head for use in bores of a larger size than those with which the other cutter-heads are used; and Fig. 10 is an end view of the cutter-head shown in Fig. 9, showing same in position, the bar being shown in cross-section.

In the drawings, A represents a lathe-chuck having the usual live-center, and B the tail-stock, having a dead-center. The rest A' is moved along the guide-rails A² by any desired mechanism. These, it will be understood, are of the usual construction.

The main essential part of our invention is the solid cylindrical bar C. This bar is splined, as at C', for about one-half its length, the spline extending to the rear end of the bar. At each end of this bar two sockets are formed, the sockets C² being on the true axial center of the bar and the sockets C³ being eccentric. Arranged on the rest A' is an angled plate D, having both its horizontal and vertical members longitudinally slotted and secured to the rest by a suitable bolt and nut, the bolt passing through the slot in the horizontal member of the plate.

In Fig. 2 we have shown a sleeve E, which is adapted to slide loosely on the bar C. This sleeve is reduced and threaded at its forward end, as at E', and a cutter-head E² is adapted to be threaded on the reduced end of the sleeve. A tail-shank E³ is formed integral with the sleeve adjacent the rear end and is adapted to engage the slot in the vertical member of the angled plate D.

In Fig. 5 we have shown the sleeve F fitting loosely on the bar C. This sleeve has formed integrally at its forward end an eccentric cutter-head F², having in its eccentric portion a diagonally-arranged slot, in which is adjustably held the cutting-tool F³. This cutting-tool is sharpened at one end, and when the sleeve is in the position shown in Fig. 5, the cutting-tool is downwardly and rearwardly inclined with respect to the bar C. The cutting-tool is held in its adjusted position by the countersunk screws F⁴. At its rear end the sleeve F is threaded, and a lever F⁵ is formed integral with a collar F⁶, which is partially threaded to fit over the threaded

portion of the sleeve F. In the non-threaded portion of the collar is secured a feather F⁷, adapted to fit the spline C' of the bar C. Adjacent the rear end the sleeve F has formed 5 on it a laterally-extending shank F⁸, similar in general construction and purpose to the shank E³. The shank F⁸, however, carries a perforated lug G, and the lever F⁵ has formed on its forward side a perforated lug G', and a 10 segmental screw G², smooth on its upper and under faces and threaded on the sides, has one end secured in the lug G' and works through the lug G, a head G³ at the free end of the segment preventing its being withdrawn from engagement with the lug G, and a 15 circular milled nut G⁴, working on the segment between the two lugs, can be adjusted to vary the throw of the lever F⁵. A suitable clamping-screw F⁹ works through one 20 side of the collar and bears upon the sleeve F, so that the collar and lever may be held against movement relative to the sleeve.

When a large bore is to be cut, the cutting-tool F³ is removed and a split band H is 25 slipped over the eccentric head F². The band H carries a feather H', adapted to fit in a spline H², formed on the under side of the head F², whereby rotation of the band on the eccentric head is prevented. The band has a 30 lateral projection H³. This projection is longitudinally slotted, and the band is also apertured on the opposite side in alinement with the slot in the projection H³. When the band is in place on the eccentrically-arranged head F², the slots in the band aline 35 with that in the head, and a cutting-tool H⁴ is arranged therein. The projection H³ forms a long substantial bearing for the cutter end of the tool and enables it to extend a considerable distance beyond the band without 40 danger of its becoming bent or sprung for lack of a suitable support. We have now described in detail the separate parts of our invention and will describe their operation on 45 two different classes of work, so as to make clear the purpose of the constructions set forth.

Where a number of pulleys or gears are to be bored to a given size, especially by inexperienced hands, the sleeve E is used with 50 the cutter-head E² of the proper size. The sleeve is slipped on the bar C, the bar projecting at both ends. The forward end of the bar is passed through the rough bore of 55 the pulley or gear in which the bore is to be finished and the forward end of the bar is placed in the live-center of the rail, using the true center or socket C² of the bar. The rear end of the bar is fixed in the dead or tail- 60 stock center. The bar C is now suspended by its true center on the centers of the lathe. The shank E³ is placed in engagement with the slot of the vertical member of the plate

D, the lathe started, and the cutter-head fed to the work by movement of the rest-block 65 imparting corresponding movement of the sleeve along the bar C, the shank and the angled plate forming the connection between the sleeve and the rest-block. The diameter of the cutter-head or mill determines the size 70 of the bore, and the sleeve is accurately guided to the work by the bar C. As the sleeve and cutter-head fit this bar snugly, though not tight enough to cause undue friction, there is no opportunity for the cutter to spring or to 75 vary from the desired diameter. The sleeve F and cutter F³ may be used to bore a hole of any size, cut internal threads, chambers, form interior grooves and sockets, and other work of like character. When this sleeve is 80 used, the bar is suspended on its eccentric sockets C³. The sleeve F is placed in position, and the proper head for the desired work is used. It is obvious that movement of the lever in either direction causes rotation of the bar, as it is keyed to the lever-collar. It will be further noted that as the 85 bar is eccentrically mounted movement of the lever in one direction, and consequent rotation of the eccentrically-suspended rod, 90 will throw the point of the cutting-tool farther toward or into the work, and opposite movement of the lever will draw the point away from the work, such movements of the tool being transverse movements as distinguished from the longitudinal movement 95 imparted by the rest-block. It is thus obvious that the lever F⁵ can be set to feed the tool according to the requirements of the special work on hand. As the least movement of this lever will cause a change in the position of the tool with reference to the article being operated on, the lever may be locked against accidental movement by means of the clamping-screw F⁹ and its 100 movement also regulated by adjusting the nut G⁴.

It will be obvious from the above that we have a lathe attachment adapted for use in a wide range of work and capable of quick and accurate adjustment to meet the demands that may be made on it where irregular boring is required.

Having thus fully described our invention, what we claim as new, and desire to secure by 115 Letters Patent, is—

1. A device of the kind described comprising a bar, a sleeve adapted to slide on the bar, an eccentric cutter-head carried by the sleeve and diagonally slotted, a split band, 120 means for clamping the band adapted to be clamped on said cutter-head, said band having a longitudinally-slotted projection and apertured in alinement with the slot in the projection said aperture and slot being adapted 125 to aline with the slot of the cutter-head, a

cutting-tool held in said slots, means for rotating the bar with reference to the sleeve, and means for moving the sleeve.

2. A device of the kind described comprising a boring-bar, having end sockets, a sleeve fitting loosely on the bar and externally threaded at one end, a cutter-head carried by the opposite end of the sleeve, a collar partially threaded to fit the threaded por-

tion of the sleeve, said collar being slidably keyed to the bar, and a handle carried by the collar.
